ROCCO FABRIZIO, OF SPRINGFIELD, MASSACHUSETTS.

WINDOW-CURTAIN FOR STREET-CARS.

1,399,253.

Specification of Letters Patent. Patented Dec. 6, 1921.

Application filed February 4, 1920. Serial No. 356,160.

To all whom it may concern:

Be it known that I, Rocco FABRIZIO, a citizen of the United States of America, residing at Springfield, in the county of 5 Hampden and State of Massachusetts, have invented certain new and useful Improvements in Window-Curtains for Street-Cars, of which the following is a specification.

This invention relates to improvements in 10 curtains for protecting car windows and especially street car windows during summer, from rain, in such a manner as to provide transparent windows from which the passengers may take observations.

15 One of the types of street cars in common use is a car having window frames adapted to be lowered into inoperative positions so as to provide relatively large window openings in the sides of the car for 20 open air riding. Should a storm come up the inside curtains are lowered for the purpose of affording a temporary protection to the passengers and of keeping the seats dry. The wind and rain deflects such curtains 25 inwardly and the end portions of the seat are consequently covered with rain so as to be unfit for use, thus reducing the capacity of the car by compelling the passengers to crowd into the center aisle. My invention 30 provides a curtain on the outside of the car which can be rolled into an inoperative position under a hood mounted on the side of the car or on the car roof or contained in a housing built in the car. This curtain is 35 provided with a series of folding or rollable transparent sections through which the passengers may look when the car is at rest or in motion to make any desired observations. The curtain is preferably held at its 40 ends against the side of the car by means of guides so as to prevent flapping and exclude rain.

With the above and other objects in view this invention relates to certain new and 45 useful combinations, constructions and arrangements of parts, clearly described in the following specification and fully illustrated in the accompanying drawings in which:

Figure 1 is a side elevation of a car 50 equipped with my improved curtain, the curtain being shown in its lower position.

Fig. 2 is a detail side elevation on an enlarged scale showing one of the end guides.

Fig. 3 is a detail view of a corner of the 55 curtain and Fig. 4 is a vertical sectional view showing the hood under which the curtain is rolled.

Referring to the accompanying drawings 5 designates a street car having a series of 60 window openings 6 which are separated from each other by vertical bars 7 which form vertical tracks for the window sashes, which are adapted to be lowered in compartments built in the side of the car. 65

On each side of the car a hood 8 of metal or other material is located either against the side of the car or under or on the side of the roof. Under this hood 70 a roller 9 is mounted to rotate and on this roller the flexible rollable curtain 10 is arranged to roll and unroll. The curtain 10 is equipped with a series of openings which are covered by transparent sections 11, which are aligned with the openings of the car. The 75 end portions of the curtain 10 are prevented from lateral displacement by means of guides 12 mounted on the sides of the car. In order to prevent sag of the central portion of the roll the hood 8 is provided 80 with a roller 13 which is supported on a depending arm 14 curved under the roller so that the central portion of said roll can rest on said roller.

By means of my improved window protection a conductor or motorman or other person may by a single operation lower the curtain to protect the window openings thereof against rain or dust or hail as the case may be. 85

In order to hold the lower edge of the curtain against the side of the car a series of eyelets 15 are provided in the lower edge of the curtain and a series of downwardly projecting hooks are provided on the car 90 which are adapted to project through the eyelets to hold the curtain downwardly.

The roller may be of a spring rotated type so that it will automatically wind the 95 curtain when desired.

Having described my invention, I claim: 100

The combination with a passenger car

constructed to provide an open side, a roller pivoted horizontally to the side of the car above the line of said opening, a roller adapted to engage the under side of said

5 roller to prevent the same from sagging, a flexible fabric on said first mentioned roller adapted to be wound and unwound thereon

and provided with a series of transparent rollable sections and means for holding said fabric downwardly so that said transparent 10 sections will cover said opening.

Signed at Springfield, Mass.

ROCCO FABRIZIO.
